UNITED STATES PATENT OFFICE.

JOHN T. GLASS, OF CENTRALIA, WASHINGTON.

TRAFFIC SIGNAL FOR VEHICLES.

Application filed March 11, 1922. Serial No. 542,962.

To all whom it may concern:

Be it known that I, JOHN T. GLASS, a citizen of the United States, residing at Centralia, in the county of Lewis and State 5 of Washington, have invented certain new and useful Improvements in a Traffic Signal for Vehicles; and I do hereby declare the following to be a full, clear, and exact description of the invention, such as will enable others skilled in the art to which it 10 appertains to make and use the same.

This invention relates to a traffic signal for vehicles.

It is generally aimed to provide a construction which will prevent vibration and relative movement of the parts thereof to the minimum, which may be made in fewer and more substantial parts than is at present the case, one in which the parts may be 20 readily adjusted or removed for inspection, cleaning or repair, and one in which the cost of construction is reduced as well as the liability of the parts to get out of order.

Another object is to provide a construction 25 which may employ several parts, particularly castings, to serve one as the signal proper and one as the lamp housing.

I further aim to provide a signal operable by means of an electro-magnet and in connection therewith to provide a means cooperating with its core to vary the throw of the signal and also to provide a clamp attachable to the signal with a connection from the clamp to the said core in the nature 35 of a yieldable spring and in connection with a return spring for the signal attachable to a mounting bracket for the magnet and to said clamp.

It is still further aimed to provide a novel 40 construction of mounting bracket for the signal and means to form a bearing for its movable parts and a means to support the electromagnet and associated parts.

Additional objects and advantages will 45 become apparent from a consideration of the description following taken in connection with accompanying drawings illustrating one practical embodiment.

In said drawings:—

50 Figure 1 is a front elevation of the improved traffic signal, showing the signal frame in an elevated or signal position;

Figure 2 is a longitudinal sectional view 55 through the signal taken centrally of the bearing tube and electromagnet;

Figure 3 is an end elevation looking to-

ward the magnet with the signal frame in full lines in a normal position and in dotted lines in an elevated position;

Figure 4 is a plan view;

Figure 5 is a cross sectional view on the line 5—5 of Figure 1 looking toward the electro-magnet and taken intermediate the same and a signal frame, and

Figure 6 is an electric diagram showing 65 the parts in circuit.

Like reference characters designate like or similar parts in the different views.

In reducing the invention to practice, a suitable bracket is provided having a body 70 or main portion at 10 and a laterally extending attaching wing 11, integral therewith. In cooperation with the wing 11 is a fastening plate 12 secured to wing 11 by adjustable bolts at 13. The free edge portions of wing 75 11 and attaching plate 12 may be U-shaped as at 14 so that such parts will coact to form a clamp in order to attach the apparatus to a suitable part of an automobile or other vehicle.

Disposed transversely through a suitable opening in the body 10 is a stationary bearing 14 in the form of a tubular shaft. A clamp plate 15 surrounds the bearing and is bolted or otherwise fastened as at 16 to the 85 wing 11 in order to rigidly maintain the bearing in place.

To the free end of the bearing 14 a lamp housing or frame 17, of any suitable shape, is secured. This housing may have a collar 90 18 to directly surround the bearing 14 and be secured against displacement by a binding set screw or the like 19 passing through the collar and engaging the bearing. Lamp housing 17 is particularly a construction 95 which may be cast or otherwise provided in a single piece. It may be appropriately adjusted longitudinally of the bearing 14 through appropriate manipulation of the binding screw 19.

The upstanding sides of the lamp housing are open as shown and covered by panels 20 which may be of glass for instance and rendered opaque for the most part but provided with transparent arrow shaped portions or signals at 21. One of these arrows 105 21 may be viewed from one side and the other from the other side of the lamp housing, as will be understood. The panels 20 are placed directly against the side edges of 110 the housing 17 and secured thereto by detachable frames 22, having flanges 23 to

overlap the ends of the housing and securing flanges 24 to overlap the top and bottom walls of the housing. Detachable set screws or other fastening means 25 may pass through the flanges 24 and into the housing. Thus a detachable frame or means enabling removal of the lenses for cleaning, replacement or otherwise is provided.

Attention is called to the fact that the panels 20 may be of appropriate colors according to local traffic regulations and that the opaqueness for the panels may be provided by mats or sheets at 26 having openings cut therein to conform in shape to the arrows 15 at 21.

Cooperating with the lamp housing 17 is a signal member generally designated 27. This member has a frame, generally rectangular at 28 provided with a ring or hub at 29 which surrounds a tube 30 journaled on the bearing 14 intermediate the collar 18 of the body 10. Frame 28 may be adjusted along the tube 30 and rigidly fastened thereto by means of a set screw 31 passing 25 through the hub 29 and binding against tube 30.

A suitable signal which may be an arrow at 32 is provided on the frame 28. Attention is called to the fact that the frame 28, hub 29 and arrow 32 form a single piece and may be provided in a single casting, whereby separate parts are avoided which would vibrate and tend to loosen in actual practice.

The frame 28 and arrow 32 are normally disposed in a horizontal position. To this end a contractile spring is provided at 33 secured by a bolt or the like at 34 fastened to a base flange integral with and extending 35 from the body 10 at 35. The bolt directly passes through a sleeve of insulation at 36. Through the adjustment of the bolt, the tension of the spring 33 may be regulated. Surrounding the spring 33 is a split clamp 37 having its terminals secured together by an adjustable bolt 38. Suitable insulation at 39 is interposed between the clamp 37 and tube 30. The other terminal of said spring 33 is fastened to the bolt 38. The urgency 40 of said spring 33 is the medium for maintaining the signal and frame in and urging it to the said horizontal position.

Mounted on and suitably insulated from the base flange 35, is an electromagnet at 40, which may be secured in place by a clamp at 41 bolted or otherwise fastened at 42 to the body 10. This electromagnet 40 may be of the solenoid type and thus provided with a slidable core or plunger at 43. Suitably secured to the plunger 43, as by a rivet or bolt at 44 is a resilient or spring strip 45 which has its upper end secured to the split clamp 37 by its bolt 38.

The lamp housing 17 is adapted to be illuminated in any suitable manner and pref-

erably from a detachable electric bulb at 46 which may be carried by a socket or holder 47 secured in the bearing 14.

The electric circuit is diagrammatically shown in Figure 6 from an inspection of 70 which it will be seen that a battery 48, which may be the starting, lighting and ignition battery of an automobile may be utilized as the source of current for the electric parts. At the same time, it is understood that any other suitable source may be employed. From the battery, a conductor 49 leads to the winding 50 of the electromagnet 40 and thence to the lamp at 46, thence back to the battery, having suitably located therein, a switch 51. It will be realized that the switch 51 may be of any approved type and arranged for actuation in any desired manner or at any appropriate location. Through the closing of the switch, the electromagnet 40 may be energized simultaneously with the lamp at 46.

In use, the apparatus may be applied at any suitable location on the automobile and when desired, more than one may be used. 90 When a signal is to be given, according to traffic regulations, switch 51 is closed which immediately illuminates the lamp 46 and energizes the electromagnet 40. As a result, the core or plunger 43 is drawn inwardly, 95 moving with it the strip 45 and causing the tube 30 to rotate on the bearing 14 and move with it the frame 28 and arrow 32 to an up-standing or signal position. When the switch 51 is open, the spring 33, which has been tensioned through the raising of the arrow 32, will restore the parts to a horizontal or normal position.

Integral with the frame 28 and disposed to project through the opening thereof at 105 the junction with the hub 29 are stop lugs 52 and 53. Projecting from the hub 29 is a stop lug 54. Spring 33 draws the parts into such relation that said lug 52 engages the lug 54 so that movement of the frame and arrow 32 to a horizontal position may be limited.

It will be noted that the tube and bearing 14 may have the conductor 49 passed therethrough for connection to the socket 37, 115 without danger of severance through relative movement of the parts.

As merely one practical embodiment has been illustrated and described, it is to be understood that changes in the details may 120 be resorted to provided they fall within the spirit and scope of the invention.

I claim as my invention:

1. A signal having a lamp housing provided with an attaching collar, a stop lug 125 extending from said collar, a signal frame extending about the housing and having a stop lug cooperating with said lug to limit movement of the frame to normal position.

2. A signal having a lamp housing pro- 130

vided with an attaching collar, a stop lug extending from said collar, a signal frame extending about the housing and having a stop lug cooperating with said lug to limit 5 movement of the frame to normal position, a hub on said frame adjacent its lug, supporting means engaged by said collar, and an actuating tube journaled on said supporting means, and said hub being secured to 10 said tube.

3. A signal having a bearing arm, a bracket having a body portion through which said bearing arm passes, a wing extending angularly from said body portion, 15 means coacting with said wing to form an attaching clamp, a base flange extending an-

gularly from the body portion, a solenoid on said base flange having a plunger, a tube journaled on said bearing arm on the opposite side of the bracket to the attaching 20 clamp carried by said tube, a clamp on said tube, a flexible connection between said clamp and said plunger, and a return spring secured to said base flange and to said clamp. 25

In testimony whereof I affix my signature in presence of two witnesses.

JOHN T. GLASS.
